UNITED STATES PATENT OFFICE.

WILLIAM J. MILLER, OF HOUSTON, TEXAS.

OIL-WELL SWAB.

Application filed October 23, 1925. Serial No. 64,411.

This invention relates to a well swab, the general object of the invention being to increase the efficiency of the device by rotatably connecting the swab to the other parts 5 so that the swab will not rotate in the casing if the other parts should have turning movement during the operation of the device, which tends to loosen the swab from the other parts.

Another object of the invention is to provide the pipe below the swab with perforations for the inlet of oil and to provide valve means for holding the oil in the pipe and above the swab on the exterior of the 15 pipe where it is visible and easily accessible.

A further object of the invention is to provide means for jarring the swab to loosen the same if it should become stuck in the well.

A still further object of the invention is to form the valve means that they will be self grinding as the device is being operated.

This invention also consists in certain 25 other features of construction and in the combination and arrangement of the several parts, to be hereinafter fully described, illustrated in the accompanying drawings and specifically pointed out in the appended 30 claim.

In describing my invention in detail, reference will be had to the accompanying drawings wherein like characters denote like or corresponding parts throughout the 35 several views, and which:—

Figure 1 is an elevation of the device.

Figure 2 is a longitudinal sectional view, showing the parts in a different position.

Figure 3 is a section on line 3—3 of Figure 1.

Figures 4, 5 and 6 are views of various parts of the device.

Figure 7 shows the swab in its lowest position.

In these views, 1 indicates a long length 45 pipe which is connected with the pipe 2 by the coupling 3, the pipe 1 being of greater diameter than the pipe 2 and the coupling 3 being made to properly connect the two 50 pipes together. The pipe 1 is provided with perforations 4 for the outlet of oil and the pipe 2 is provided with perforations 5 for the inlet of oil. A rope socket 6 is connected with the upper end of the pipe 1 55 for receiving the cable 7 and the lower end of pipe 2 is closed by a plug 8.

The swab 9, which is preferably formed of rubber or the like, is carried by a tube 10 which is slidably mounted on a part of the pipe 2. The swab is held in place on 60 the tube by the upper and lower nuts 11 threaded to the tube and the washers 12 which are placed between the nuts and the ends of the swab. A jar member 13 is connected with the upper end of the tube 65 10 and cooperates with a jar part 14 formed on the lower end of the coupling 3. A valve part 15 is connected with the lower end of the tube 10 and cooperates with a valve part 16 connected with the lower end 70 of the pipe 2, below the perforations in said pipe. The part 15 has an annular groove 17 therein for receiving an annular flange 18 on the part 16.

From the foregoing, it will be seen that 75 the swab is swiveled on the pipes so that said pipes can have turning movement without the swab turning and thus there is no danger of the parts becoming disconnected by the twisting movement of the pipes with the swab remaining stationary as there is when the swab is firmly connected with the pipes.

As the device descends, the part 14 will press upon the part 13 and thus force the swab to move downwardly with the rest 80 of the device and in this position of the parts, the valve parts will be separated and the perforations 5 will be exposed so that when the device enters the liquid in the well, said liquid will pass through the perforations and flow upwardly through the pipe 85 2 into the pipe 1 and will escape through the perforations 4 into the well casing above the swab.

On the upward stroke, the swab remains stationary as the parts pass upwardly 90 until the valve part 16 strikes the part 15, when the swab is moved upwardly with the other parts. The engagement of the two 95 valve parts prevents the liquid from returning to the well as the perforations 5 are covered by the tube 10 and any leakage from 100 between the pipe and tube is stopped by the valve part. As the device is being reciprocated by the cable, the said cable has a tendency to turn the parts but this turning movement is not transmitted to the swab, as before explained, but the movement of the 105 valve part 16 in relation to the part 15 makes the valve parts self-grinding, as the flange 18 turns in the groove 17. The jar parts 13 and 14 enables the swab to be loosened if 110 it should become stuck in the well by letting

the part 14 fall upon the part 13 to set up a jarring action. The valve parts are visible so that they are easily accessible and the perforated part of pipe 2 is below the swab 5 on the downward stroke of the device so that the liquid can enter the device through said perforations and after flowing through the portion of the pipe which passes through the swab, will escape from the perforated 10 part of the pipe 1 above the swab.

It is thought from the foregoing description that the advantages and novel features of my invention will be readily apparent.

I desire it to be understood that I may 15 make changes in the construction and in the combination and arrangement of the several parts, provided that such changes fall within the scope of the appended claim.

What I claim is:—
20 A pump plunger of the character de-

scribed comprising a hollow stem having inlet openings adjacent the lower end thereof, and outlet openings adjacent the upper end thereof, a sleeve loosely mounted on said stem and capable of rotation with relation thereto, a swab fixed on said sleeve, said sleeve projecting above and below the swab and exteriorly threaded, a valve member threaded on the lower end of the sleeve and formed with an annular groove, and a co- 25 operating valve member carried by the lower end of the stem for movement toward and away from the first mentioned valve member, and including an annular flange adapted to be seated in said groove when the valve 30 is closed for the purpose specified.

In testimony whereof I affix my signature.

WILLIAM J. MILLER.
